CLAIM

The ornamental design for a speaker box, as shown and described.

DESCRIPTION

1. Speaker box

1.1 : Perspective

1.2 : Front

1.3 : Back

1.4 : Left

1.5 : Right

1.6 : Top

1.7 : Bottom

1.8 : Perspective

1.9 : Enlarged

1. Purpose of this design product: the present design product is used to play audio; 2. Design point of this design product: shape of the design; 3. Drawings that best embodies the design point of this design: FIG. 1.1; 4. The dash-dash broken lines in the drawings depict the portions of the Speaker box which form no part of the claimed design; 5. The dot-dash broken lines in the drawings depict the boundaries of the partial enlarged views that form no part of the claimed design; the labels 1.9 in reproduction 1.1 form no part of the claimed design.

1 Claim, 9 Drawing Sheets
